UNITED STATES PATENT OFFICE

2,424,606

PRINTING DEVICE

Max Engler, Akron, Ohio, assignor to The General Tire & Rubber Company, Akron, Ohio, a corporation of Ohio

Application September 4, 1944, Serial No. 552,603

4 Claims. (Cl. 101—212)

1

This invention relates to devices for printing upon stock being advanced over a supporting bed, and more particularly to a device suitable for printing upon rubber stock, such as tire tread stock.

The present invention has for an object to provide a simple printing device of the character described, which is suitable for printing with an ink containing latex.

It is also an object of the invention to provide an inking mechanism in which the transfer rollers are so driven that a minimum excess of ink is maintained at the bights of the rollers.

A further object of the invention is to provide a printing mechanism that is readily adjustable into and out of operative position with respect to the stock to be printed upon and with respect to a stationary ink receptacle.

A further object of the invention is to provide a printing device having a printing roller that is held by gravity in printing position and that is provided with an adjustable counterbalance to regulate the pressure of the printing roller against the stock.

An additional object of the invention is to provide a printing device that is movable into and out of printing position with respect to the traveling stock, and also adjustable laterally of the supporting bed over which the stock is fed.

With the above and other objects in view, the invention may be said to comprise the device as illustrated in the accompanying drawings, hereinafter described and particularly set forth in appended claims, together with such variations and modifications thereof as will be apparent to one skilled in the art to which the invention pertains.

Reference should be had to the accompanying drawings forming a part of this specification, in which:

Fig. 1 is a top plan view showing the printing device of the present invention applied to a horizontal stock feeding bed;

Fig. 2 is a side elevation of the bed and printing device shown in Fig. 1;

Fig. 3 is a section taken on the line indicated at 3—3 in Fig. 1;

Fig. 4 is an enlarged section taken on the line indicated at 4—4 in Fig. 3;

Fig. 5 is an enlarged section taken on the line indicated at 5—5 in Fig. 4;

Fig. 6 is a side elevation of one of the type clamping plates;

Fig. 7 is a plan view of a type segment, and

2

Fig. 8 is a side elevation of the segment shown in Fig. 7.

Referring to the accompanying drawings, the printing device of the present invention is shown applied to a stock feed bed which comprises a supporting frame 1 and a traveling belt 2 upon which stock such as tire tread stock S is carried, a rigid support for the belt 2 such as a roller 3 being provided at the point where the printing operation is performed.

Suitable guides 4 are attached to the frame 1 at opposite sides thereof and provide a support below the belt 2 for a transverse slide 5 that carries standards 6 which project upwardly on opposite sides of the belt 2. A screw 7 that is rotatably mounted in a suitable bearing 8 on the frame 1 has threaded engagement with one of the standards 6 and carries a hand wheel 9 by means of which it may be turned to adjust the slide 5 transversely of the bed.

The standards 6 carry bearing caps 10 at their upper ends in which a transverse shaft 11 is journaled, the shaft 11 being held against endwise movement by means of collars 12 attached to and engageable with the inner faces of the caps 10. One of the standards 6 has a bracket 13 attached thereto and extending inwardly over the belt 2 to adjacent the center thereof and supporting at its inner end an ink receptacle or tray 14 which is positioned adjacent the shaft 11 and forwardly thereof.

An arm 15 has a collar 16 at its inner end which is attached to the shaft 11 and carries a transverse shaft 17 at its outer end. The shaft 17 has a printing roller 18 rotatably mounted thereon which is adapted when the arm 15 is in its lowermost position, to engage with the stock S on the belt 2. A rearwardly extending arm 19 is attached to the shaft 11 and has a counterweight 20 slidably mounted thereon, the counterweight 20 being secured in adjusted position on the arm 19 by means of a set screw 21. The printing roller 18 is normally held by gravity in engagement with the stock and pressure exerted by the roller 18 on the stock is regulated by means of the weight 20 which is adjustable on the arm 19 to counterbalance as much of the weight of the roller 18 and associated parts as desired.

Adjacent its inner end, the roller supporting arm 15 carries a transverse shaft 22 upon which a roller 23 is rotatably mounted. The shaft 22 also provides a pivot for an upwardly extending arm 24 that carries a transverse shaft 25 at its outer end, upon which a roller 26 is rotatably mounted. Intermediate the ends thereof, the

arm 24 has a lateral extension 27 which carries a transverse shaft 28 that supports a roller 29 that has tangential engagement with the rollers 23 and 26. The arm 24 carries a laterally extending bracket 30 that overlies the arm 15 and which carries an adjustable stop screw 31 that engages with the top edge of the arm 15. The arm 24 is normally supported in a forwardly inclined position with the screw 31 engaging the arm 15, in which position the upper roller 26 is in position to engage with type carried upon the periphery of the printing roller 18. The arm 24 and rollers carried thereby are held in operative position by gravity, and the arm 24 and its rollers which serve to transfer ink from the tray 14 to the type on the roller 18, can be swung to a position clear of the printing roller when desired. The lower roller 23 is positioned to enter the inking tray 14 when the printing roller is moved downwardly to operative position, the roller 23 being movable upwardly out of the inking tray when the arm 15 is swung upwardly to shift the printing roller 18 to an inoperative position.

The periphery of the roller 18 has frictional engagement with the traveling stock which rotates the printing roller as it passes beneath the same. The type on the printing roller has frictional engagement with the upper ink transfer roller 26 to impart turning movements to the roller 26 during passage of the type past the point of tangential contact. The roller 29 is driven by the roller 26 solely by the friction at its points of tangential contact with the roller 26, and the roller 23 is driven by the roller 29 solely by the friction at its points of tangential contact with the roller 29. When the surfaces of the rollers 23, 26 and 29 are covered with ink the coefficient of friction at the points of tangential contact is greatly reduced and only slight torque is transmitted from one of the rollers to another. The reduced friction will cause the roller 26 to slip on the roller 29 and the roller 29 to slip on the roller 23 so that the speed of the rollers 23 and 29 is reduced to such an extent that a very thin film of ink will be maintained upon the peripheries of the rollers and very little ink will accumulate in the bights between the rollers. When the peripheral surfaces of the rollers are dry, the friction is sufficient to cause the rollers to be driven substantially without slippage to quickly wet the rollers, and after the surfaces of the rollers are wet with ink, slippage between the rollers prevents the accumulation of an excess of ink on the roller surfaces. Since the ink employed for printing on rubber often contains substantial amounts of latex, it is desirable that the ink be carried in thin films and that accumulations in the bights of the rollers that might solidify on the rollers be avoided.

The printing roller 18 has a continuous circumferential type receiving seat 32 and a flange 33 at one side which projects outwardly beyond the seat 32. Inwardly of the seat 32 the roller 18 is recessed on the side opposite that having the flange 33, and has an annular positioning shoulder 34 spaced inwardly from the seat 32. The recessed face of the roller 18 has regularly spaced radial grooves 35 which extend inwardly from the seat 32 to the shoulder 34. Type segments 36 are mounted in the periphery of the roller 18 on the circumferential seat 32, and these segments carry raised characters 37. The segments 36 are clamped against the flange 33 by means of a series of sector shaped plates 38

that are mounted side by side with their side edges abutting and with their inner ends resting upon the positioning shoulder 34. The inner faces of the plates 38 are recessed at their outer edges to provide flanges 39 for engagement with the outer side edges of the segments 36 and shoulders 40 for engagement with the inner faces of the segments 36. Each plate 38 is provided with a central radial rib 41 that fits in a radial groove 35 on the side face of the roller 18, and each plate is provided with a central opening 42 which receives a clamping screw 43 that extends through the opening and screws into the body of the roller 18.

The sector shaped plates 38 are preferably identical as shown in Figs. 2 and 4 and the type segments 36 are preferably of a length corresponding to the width of a sector plate 38 at its outer end. The type segments 36 may be spaced circumferentially on the periphery of the roller 18 with each segment engaged by one of the clamping plates 38. If the ends of the segments 36 are flush with the edges of the plate 38 by which it is held in place, adjacent plates 38 may be adjusted to positions in which they engage the ends of the segments 36 to hold the same against movements circumferentially of the roller.

The roller 18 preferably bears against the stock S with sufficient pressure to maintain frictional engagement with portions of the roller intermediate the raised type segments, as well as with the type segments, so that the peripheral travel of the roller 18 will correspond to the linear travel of the stock. The roller 26 may be so adjusted with respect to the roller 18 by means of the screw 31 that it will be engaged only by the raised characters on the segments 36 so that turning movements will be imparted to the ink transfer rollers only during the periods during which the roller 26 is rolling over the raised characters on the type segments. This intermittent movement of the transfer rollers also reduces the rate at which ink is picked up from the tray by the roller 23 and assists in preventing the accumulation of an undesirable excess of ink on the surfaces of the rollers.

It is desirable that the transfer rollers be formed of rubber-like material that is resistant to solvents that may be present in the ink and these rollers may, therefore, be advantageously made of a synthetic rubber composition such as neoprene.

It is to be understood that variations and modifications of the specific device herein shown and described for purposes of illustration, may be made without departing from the spirit of the invention.

What I claim is:

1. A printing device adapted to be mounted adjacent a bed over which the stock to be printed upon may be advanced and comprising a support, an ink tray mounted in fixed position on the support, and a train of tangentially contacting rollers mounted on the support for movement bodily toward or away from the bed, one end roller of said train being a printing roller engageable with the stock on said bed and the other end roller being movable with the arm into and out of the ink tray and positioned in the ink tray when the printing roller is in stock engaging position.

2. A printing device adapted to be mounted above a bed over which the stock to be printed upon may be passed and comprising a support

including a pivot shaft extending transversely over the bed, an ink tray carried by the support alongside the shaft, a vertically swinging arm carried by the shaft and extending past said ink tray, a printing roller carried by the arm at its outer end, and tangentially engaging ink transfer rollers carried by said arm, said arm being movable about the axis of said shaft to shift the printing roller into or out of stock engaging position, one of said ink transfer rollers being positioned directly over the ink tray, movable with said arm into and out of the tray and positioned in the tray when the printing roller is in stock engaging position and another of said transfer rollers being in tangential engagement with the printing roller.

3. A printing device adapted to be mounted above a bed over which the stock to be printed upon may be passed and comprising a support including a pivot shaft extending transversely over the bed, an ink tray carried by the support alongside the shaft, a vertically swinging arm carried by the shaft and extending past said ink tray, a printing roller carried by the arm at its outer end for movement into and out of engagement with the stock, tangentially contacting transfer rollers carried by said arm for transferring ink from said tray to said printing roller, one of the transfer rollers engaging with the printing roller and another being movable into and out of said ink tray as said arm is moved to shift the printing roller into and out of engagement with the stock, a second arm attached to said shaft and a counterweight adjustably mounted on said arm for regulating the pressure with which the printing roller engages the stock.

4. A printing device adapted to be mounted

above a bed over which the stock to be printed upon may be advanced and comprising a support, a pivot shaft carried by said support and extending transversely over said bed, a vertically swinging arm carried by said shaft, a printing roller rotatably mounted upon the outer end of said arm and adapted to be driven by frictional engagement with the traveling stock, an ink tray carried by the support adjacent the shaft and in fixed position with respect thereto, and tangentially contacting rollers carried by said arm for transferring ink from said tray to said printing roller, said transfer rollers and printing roller being in tangential contact, each with one of the others, the transfer rollers being driven by the printing roller and one by another solely by friction at the points of tangential contact of their ink carrying faces.

MAX ENGLER.
